Attorney.

UNITED STATES PATENT OFFICE.

WILLIAM E. SHARPLES, OF FALL RIVER, MASSACHUSETTS.

LET-OFF MECHANISM FOR LOOMS.

SPECIFICATION forming part of Letters Patent No. 445,383, dated January 27, 1891.

Application filed November 25, 1887. Serial No. 256,051. (No model.)

To all whom it may concern:

Be it known that I, WILLIAM E. SHARPLES, of Fall River, in the county of Bristol and State of Massachusetts, have invented a new 5 and useful Improvement in Let-Off Mechanisms for Looms; and I do hereby declare the following specification, taken in connection with the accompanying drawings, forming a part of the same, to be a description thereof.

This invention has for its main object the conversion of a toothed wheel into a band wheel or pulley, and it is particularly adapted to looms when it is desired to substitute a friction let-off mechanism for one in which a 10 pallet-wheel or other toothed wheel is employed as an active element—as, for instance, in the well-known “bob-wire” let-off motion.

The invention consists in certain features of construction and arrangement hereinafter 15 described and claimed.

In the accompanying drawings, Figure 1 represents a rear view of a portion of a loom in which the pallet-wheel that is usually mounted on a shaft geared to the warp-beam 20 is furnished with a band-rim or pulley-face, and a friction-band is passed around said rim or pulley-face and is connected with the “vibrator.” Fig. 2 shows a section through the warp-beam and the vibrator on line Y Y of

Fig. 1, the gear on the beam being shown by 25 a dotted circle and the frame of the loom being omitted. Fig. 3 represents an end view of a portion of a loom in which a two-part ring or annulus that forms a band-rim or pulley-face is secured to the pallet-wheel to make such wheel a pulley, and a friction-band is passed around said band-rim and connected with the vibrator. Fig. 4 shows a horizontal section, on line Z Z, Fig. 3, through the pallet-wheel and the band-rim attached thereto.

Fig. 5 represents an end view of a portion of a loom provided with the well-known bob-wire let-off mechanism in which a pallet-wheel is employed.

In looms as ordinarily constructed the warp 40 a passes from the beam A over a vibrator B, and thence through the harnesses and the reed of the lathe over the breast-beam to the receiving or cloth roller in a well-understood way. The warp-beam is provided with a gear

A', which meshes with a pinion G, located on a shaft g.

When the bob-wire let-off mechanism is employed, the shaft g is furnished with a pallet-wheel N, Fig. 5, and a pallet O is pivoted to the frame of the loom above said wheel so as to operate thereon. A hanger P is pivoted to the forward end of an arm J, and said hanger has secured thereto a bob-wire or rod p, whose lower end is located just above one end of the pallet. The arm J is attached to one end of the vibrator B, which is a rock-shaft having a radially-projecting leaf b, and said arm is provided with a weight j and with a stop-finger j', which finger determines the normal position of the wire or rod p with relation to the pallet O. When the vibrator and its arm J are rocked by a strain upon the warp, which strain is produced by the forward movement of the lathe in beating up a pick, 60 the wire or rod p will depress the forward end of the pallet, thereby allowing the wheel N to turn one tooth and a small quantity of yarn to be delivered from the beam A.

It is often very desirable to substitute a 65 “friction” let-off mechanism (in which a pulley and a band passing around the same are used) for one in which a pallet-wheel or other toothed wheel is employed; but as such wheels are usually secured to their shafts, so they 70 cannot be removed without considerable loss of time and much trouble, such a substitution becomes comparatively costly, (if the toothed wheel be taken off and a pulley be put on,) as well as entailing an equal amount of time 75 and trouble when it is desired to remove the friction let-off and use one in which a toothed wheel is employed.

By arranging to convert the toothed wheel into a pulley in accordance with my invention the change is greatly simplified, and this may be effected by securing to such toothed wheel in any preferred manner a band-rim or pulley-face, as R, of any preferred form. If the friction-band to be used be in the form of a rope, then the face of the ring or band-rim R may be provided with a circumferential groove; but if the friction-band be a flat belt then the face of the ring may be flat.

For convenience in applying and removing 100

the band-rim or pulley-face R, I prefer to make it in two parts or halves, as shown in Fig. 3, and bolt said parts together, as at r, so the ring will be immovable on the toothed wheel.

By dispensing with the pallet O and the hanger P and its wire p and passing a friction-band K around the ring or pulley-face R, and properly attaching the ends of said band, a friction let-off is secured. As shown in Fig. 3, one end of the band K is attached to the arm J and the other end is preferably secured to a hook or support L, projecting from a slotted plate l', through which a bolt l passes into the frame of the loom, so said hook can be adjusted on the frame to take up any stretch in the band K should occasion require; but in place of attaching one end of the band to the hook L said end may be secured to the arm J, as shown by dotted lines in Fig. 3.

From the foregoing it will be understood that a toothed wheel can be converted into a pulley by attaching the band-rim thereto, and that when such band-rim is applied to the

pallet or other toothed wheel of a let-off mechanism it enables a friction let-off to be used on the loom.

What I claim, and desire to secure by Letters Patent, is—

1. The combination, with a toothed wheel, of a band-rim secured to the periphery of the toothed wheel, substantially as set forth.

2. A toothed wheel for let-off mechanisms for looms for weaving, having a band-rim detachably secured to the periphery of the toothed wheel, substantially as set forth.

3. The combination of the warp-beam and its gear A', the shaft g, having a pinion G, a toothed wheel secured to said shaft, a band-rim or pulley-face secured to said toothed wheel, a weighted vibrator, and a friction-band K, passed partially around said band-rim or pulley-face and connected with the vibrator, substantially as set forth.

WILLIAM E. SHARPLES.
